CAR ROOF

Filed April 11, 1942

UNITED STATES PATENT OFFICE

2,335,383

CAR ROOF

Charles David Bonsall, Chicago, Ill., assignor to
 Standard Railway Equipment Manufacturing
 Company, a corporation of Delaware

Application April 11, 1942, Serial No. 438,546

7 Claims. (Cl. 108—5.4)

This invention relates to metal car roof constructions of the type shown in my Patent No. 1,627,372 wherein the roof sheets extend from side plate to side plate of the car and have raised panels along their adjacent margins and upstanding flanges along the adjacent edges of said panels that are rigidly connected by a seam cap having outstanding base flanges that rest on said panels, whereby said panels, flanges and seam cap cooperate so as together to form a standing seam construction which functions as an outside carline or load carrying member of the roof construction. The principal object of the present invention is to increase the strength, rigidity, durability and weatherproofing qualities of the above seam construction. The invention consists in continuing the base flanges of the seam cap outwardly beyond the raised side marginal panels of the roof sheets and thence offsetting the marginal portions of said base flanges downwardly to bear against the lower plane portions of said sheets, thereby providing clear spaces between said base flanges and said sheets along said panels that serve as drain channels for any water that leaks beneath the outer edges of said base flanges and that also serve to break the line of contact between said base flanges and sheets and thus prevent flow of water through the seam by capillary attraction. The invention also consists in the parts and in the arrangements and combinations of parts hereinafter described and claimed.

In the accompanying drawing, which forms part of this specification and wherein like symbols refer to like parts wherever they occur,

Fig. 1 is a plan view of a portion of a car roof construction embodying my invention.

Fig. 2 is an enlarged vertical transverse section through the eaves portion of the roof, the section being taken adjacent to one of the roof seams on the line 2—2 in Fig. 1.

Fig. 3 is a fragmentary perspective view of the eaves portion of the roof in the region of one of the roof seams.

Figs. 4 and 5 are enlarged fragmentary vertical longitudinal sections through the roof on the lines 4—4 and 5—5, respectively, in Fig. 2; and

Fig. 6 is a fragmentary horizontal section through the roof at the side plate on the line 6—6 in Fig. 2.

In the accompanying drawing, my invention is shown embodied in a car roof comprising metal side plates A of substantially Z-shaped cross-section with the inner legs 1 upstanding and having inwardly extending top flanges 2 disposed at

an angle conforming to the pitch of said roof. Metal roof sheets B span from side plate to side plate and rest on the inwardly extending top flanges 2 thereof. The roof sheets have depending eaves flanges 3 that overhang the upstanding inner legs 1 of the side plates A and are rigidly secured to the outer faces of the inner legs 1 thereof by horizontal rivets 4.

As shown in my Patent No. 1,627,372, the roof sheets B have raised flat-topped panels 5 along their adjacent side margins and upstanding flanges 6 along the edges of said margins that are covered by an inverted U-shaped metal seam cap C that is secured by rivets 7 to said flanges and has outstanding base flanges 8 that seat on said panels, whereby said panels, flanges and seam cap cooperate so as together to form a rigid standing seam which functions as a load carrying member or outside carline of the roof structure. As shown in the drawing, the seam cap C and seam flanges 6 decrease in depth from points inwardly of the side plates to the eaves where they are turned down with the eaves flanges 3 over the vertical inner legs 1 of said side plates. As the depth of the seam flanges 6 and seam cap C decreases, there is a corresponding increase in the width of the raised side marginal panels 5 of the roof sheets and the base flanges 8 of said cap towards the eaves, said base flanges 8 and panels terminating flush with the lower edge of the depending eaves flanges 3 of the roof sheets.

According to the present invention, the outstanding base flanges 8 of the seam cap C are extended, as at 9, beyond the inclined shoulders 10 formed on the roof sheets by the raised side marginal panels 5 thereof and are thence inclined downwardly, as at 11, at an angle corresponding substantially to the slope of said shoulders to the lower plane portions of said sheets where they terminate in depressed side marginal panels 12 that seat or bear upon said lower plane portions of said sheets. As shown in Fig. 6, a filler plate 13 is disposed between the upstanding leg 1 of each side plate and the downturned end of the side marginal panels 5 of adjacent roof sheets and is held in place by the rivets 4 that secure the depending eaves end of the roof sheets and seam caps to the side plates. By this arrangement, spaces 14 are provided between the roof sheets and the base flanges 8 of the seam cap along raised side marginal panels 5 of said sheets, and these spaces extend continuously from end to end of said sheets and cap, including the downturned eaves portions thereof, and are pref-

erably left open to the atmosphere at their lower ends. The spaces 14 serve as drain channels or passageways for carrying away any water that leaks beneath the depressed outer margins 12 of the base flanges 8 of the seam cap; they also serve as ventilating channels to keep said spaces dry; and they also serve to break the line of contact between the roof sheets and said base flanges and thus prevent further flow of water into the seam by capillary attraction. The outwardly extended downwardly offset portions of the seam cap also serve to increase the strength, rigidity and durability of the standing seam construction, as well as increasing the weatherproofing qualities thereof.

What I claim is:

1. A car roof comprising side plates, roof sheets extending from side plate to side plate and having raised flat-topped panels along their adjacent margins and upstanding flanges along the adjacent edges of said panels, and seam caps covering said flanges and having outstanding base flanges which seat on said panels and extend outwardly therebeyond and have depressed marginal panels which seat on the body portions of said sheets, thereby providing spaces between said roof sheets and base flanges along the remote sides of said panels.

2. A car roof comprising side plates, roof sheets extending from side plate to side plate and having raised flat-topped panels along their adjacent margins and upstanding flanges along the adjacent edges of said panels, and seam caps covering said flanges and having outstanding base flanges which seat on said panels and extend outwardly therebeyond and have depressed marginal panels which seat on the body portions of said sheets, thereby providing spaces between said roof sheets and base flanges along the remote sides of said panels, said roof being turned down over and rigidly secured to the vertical faces of said side plates and said spaces being left open at the ends.

3. A roof for a railway car having spaced side plates, said roof comprising roof sheets extending between and secured to the side plates and having body portions with raised panels along their adjacent margins with upstanding flanges along the adjacent edges of said panels, and a seam cap straddling said flanges and having outstanding base portions which extend outwardly

beyond said panels and have depending marginal portions which engage the body portions of said roof sheets, thereby providing spaces between said roof sheets and said base portions along the remote sides of said panels.

4. A roof for a railway car having spaced side plates, said roof comprising roof sheets extending between and secured to the side plates and having body portions with raised panels along their adjacent margins with upstanding flanges along the adjacent edges of said panels, and a seam cap straddling said flanges and having outstanding base portions which engage said raised panels and which extend outwardly beyond said panels and have depending marginal portions which engage the body portions of said roof sheets, thereby providing spaces between said roof sheets and said base portions along the remote sides of said panels.

5. A car roof as defined in claim 3, wherein the roof sheets, raised panels and seam cap are turned down over the side plates and said spaces are open at the lower ends thereof.

6. A roof for a railway car having spaced side plates, said roof comprising roof sheets extending between and secured to the side plates and having body portions with raised panels along their adjacent margins, and a seam cap secured to said roof sheets and overlying said raised panels and having portions which extend outwardly beyond said panels and have depending marginal portions which engage the body portions of said roof sheets, thereby providing spaces between said roof sheets and said portions along the remote sides of said panels.

7. A roof for a railway car having spaced side plates, said roof comprising roof sheets extending between and secured to the side plates and having body portions with raised panels along their adjacent margins with upstanding flanges along the adjacent edges of said panels, and a seam cap straddling said flanges and having outstanding base portions which extend outwardly beyond said panels and have depending marginal portions which extend below the level of the tops of said panels into proximity to the body portions of the roof sheets, thereby providing spaces between said roof sheets and said base portions, along the remote sides of said panels.

CHARLES DAVID BONSALL.
